UNITED STATES PATENT OFFICE.

JOHN C. DUEBER, OF CANTON, OHIO.

DESIGN FOR A WATCH-CASE.

SPECIFICATION forming part of Design No. 21,720, dated July 19, 1892.

Application filed June 13, 1892. Serial No. 436,613. Term of patent 14 years.

To all whom it may concern:

Be it known that I, JOHN C. DUEBER, a citizen of the United States, and a resident of Canton, county of Stark, State of Ohio, have 5 invented a new and useful Design for Watch-Cases, of which the following is a full, clear, and exact description, reference being had to the accompanying drawings, making part of this specification.

10 Figure 1 is a view in perspective of a watch-case, illustrating my design; and Fig. 2 is an edge view of the same.

On the lids and central thereto is shown a scalloped-edged oblong portion A, from which 15 radiates a series of engraved flat alternate lobes B and C, which increase in breadth as they approach the perimeter of the lid and which are rounded at their ends, the former B ornamented in vermicelli *a* and the other C 20 with parallel transverse lines *b* and a branch *c*, with leaves, the lobes inclosed by a single line or loop *d*, the whole figure inclosed by

the double lines *e*. The bezel portion D of the lid is a flat bevel ornamented by a series of oval ribs *h*, between which is shown an oval 25 rim E, ornamented with a vermicelli design.

The leading features of my design are the scalloped-edged oblong portion A, the alternate lobes B and C, the flat beveled bezel D, ornamented with a series of oval ribs, and the 30 vermicelli scroll covering the oval rim E or edge of the watch-case between the ribbed bezels D, as shown.

What I claim, and desire to secure by Letters Patent, is—

35 The design for a watch-case, as herein described and shown.

In testimony whereof I have hereunto set my hand this 23d day of May, A. D. 1892.

JOHN C. DUEBER.
